J. KRONSER,
MOLD FOR MAKING PIG TROUGHES.
APPLICATION FILED JAN. 27, 1917.

Patented May 8, 1917.

THE MORRIS PETERS CO., PHOTO-LITHO., WASHINGTON, D. C.

UNITED STATES PATENT OFFICE.

JOHN KRONSER, OF APPLETON, WISCONSIN.

MOLD FOR MAKING PIG-TROUGHES.

1,225,650.

Specification of Letters Patent.

Patented May 8, 1917.

Application filed January 27, 1917. Serial No. 144,907.

To all whom it may concern:

Be it known that I, JOHN KRONSER, a citizen of the United States, residing at Appleton, in the county of Outagamie and State 5 of Wisconsin, have invented certain new and useful Improvements in Molds for Making Pig-Troughs, of which the following is a specification.

This invention relates to certain new and 10 useful improvements in pig troughs and molds for making the same.

One of the objects of the invention is to provide a pig trough of elongated construction that is formed of concrete, cement or 15 similar material with metallic reinforcing bars therein for strengthening the same and with laterally-extending feet at the opposite ends to insure the trough at all times to assume an upright position and obviate danger of the same being turned over.

A further object of the invention is to provide an improved form of mold for forming the trough in which the mold is composed of relatively few disconnected 25 parts, and a device that is extremely simple in construction and operation and one that can be assembled in an easy manner by a single operator if necessary.

A further object of the invention is to 30 provide a mold for a pig trough of the type herein disclosed wherein the sides of the mold are bodily disconnected from the remaining structure in assembling and disassembling the parts while the end walls of 35 the mold are hinged to the bottom and carry side extensions which coöperate with the adjacent ends of the removable sides.

With these general objects in view and others that will appear as the nature of the 40 invention is better understood, the same consists in the novel construction, combination and arrangement of parts hereinafter more fully described, illustrated in the accompanying drawings, and then claimed.

45 In the drawing forming a part of this application and in which like designating characters refer to corresponding parts throughout the several views:—

Figure 1 is a perspective view of a pig 50 trough formed by the mold herein disclosed.

Fig. 2 is a longitudinal sectional view of

a mold built in accordance with the present invention, the central portion thereof being broken away and showing in section a portion of the longitudinal core member as well 55 as the reinforcing bars for the concrete.

Fig. 3 is a top plan view of the same with the central portion thereof broken away.

Fig. 4 is a cross-sectional view taken on line IV—IV of Fig. 3.

Fig. 5 is a detail perspective view of one end portion of the mold with the bottom broken away and the sides removed, and,

Fig. 6 is a perspective view of one of the removable side members, with the central 65 portion thereof broken away, and illustrating more clearly the means for removably securing the same to the mold body.

Referring more in detail to the accompanying drawing and particularly to Fig. 1 70 which discloses the form of pig trough built by the mold disclosed herein, it will be seen that the trough includes inclined side walls —a— and —b— which present a trough of substantial V-shape in cross-section while the 75 end blocks —c— carry lateral extensions —d— which project the desired distance beyond the sides of the trough to insure the same assuming an upright position at all times and obviating danger of the trough 80 upsetting.

The mold for forming the trough is more clearly shown in Figs. 2 to 6 and the same being formed of any suitable material, either wood or metal, includes a flat bottom 85 10 preferably of rectangular configuration while end walls 11 are hinged thereto as at 12 as clearly shown in Figs. 2 and 5. As shown in said figures, the lower edges of the end walls 11 rest upon the upper face of 90 the bottom 10 while the opposite ends of the end walls have permanently secured thereto as at 13 inward extensions 14 which lie flush with and engage the opposite sides of the bottom 10. It will be seen that when the end 95 walls 11 are moved on their hinges 12, the inner extensions 14 will be moved therewith to permit the contents of the mold to be readily removed therefrom.

The mold slides are more clearly shown 100 in Figs. 3 and 6 and include main portions 15 having right-angular extensions 16 at

opposite ends thereof, the outside faces 17 of the extensions being perpendicular to the bottom 10 of the mold while the inner faces 18 of the sides 15 converge downwardly as shown in Fig. 4 to give the desired incline to the side walls —a— and —b— of the trough.

In assembling the mold parts, the end walls 11 of the mold are moved to the position shown in Fig. 5 and the side walls 15 are positioned so that the outer faces 17 of the angular extensions 16 lie juxtaposed to the inner faces of the end wall extensions 14 as clearly shown in Fig. 3. The parts are held in this position by the angle iron straps 19 which have the angle ends 20 thereof spaced from the faces 17 a distance equal to the thickness of the end wall extensions 14 so that when assembled the end wall extensions 14 lie between the strap ends 20 and the side extensions 16 as clearly shown in Fig. 3, and are so held by frictional engagement.

With the mold parts positioned as described, a quantity of the plastic material such as concrete or cement is placed therein and the central core 21 of substantial triangular configuration as shown in Fig. 4 is placed therein as illustrated and tends to spread the plastic material in a manner to fill the mold to a point level with the upper edges of the side and end walls. During the process of filling the mold with the plastic material, longitudinal reinforcing bars 22 are placed therein as well as transverse reinforcing bars 23 at the ends thereof. It will be observed upon an inspection of Fig. 3 that there is a substantially rectangular pocket formed at each end of the mold by the end wall, inner extensions carried thereby and the angular extensions on the side walls 15, which construction of the mold causes the lateral extensions —d— on the end blocks —e— of the trough.

When the plastic material has been allowed to set and assume the desired hardness the mold parts are disassembled by first moving the end walls 11 on their hinges 12, which movement carries the end wall extensions 14 outwardly of the mold bottom 10 and from its engagement with the straps 20 of the side walls 15, and in this position the side walls may be readily removed laterally of the mold bottom so that the trough alone containing the core remains upon the mold bottom. In any well-known manner, the core 21 may be then removed and the completed pig trough removed from the mold bottom 10 and if necessary, finished in the desired manner.

It will be noted that there is provided a pig trough and mold for the same which is extremely simple in construction and operation and one that is inexpensive to manu-

facture and while I have shown and described the preferred form of the invention, it is nevertheless to be understood that various forms, modifications and arrangements of the parts may be made without departing from the spirit and scope of the invention as claimed.

What I claim as new is:

1. A trough mold including a bottom of rectangular configuration, end walls hinged thereto with the lower edges thereof resting upon the upper face of the bottom, inward extensions carried by the opposite ends of the end walls with the inner faces thereof engaging the outer side edges of the bottom, bodily removable sides for the mold, each side having an angular extension projecting in the same direction, the outer faces of the angular extensions being perpendicular to the mold bottom, the inner faces of the side walls converging downwardly, the perpendicular outer faces of the extensions adapted to lie juxtaposed to the inner faces of the end wall extensions, metallic angle straps fixed to the side walls and adapted to engage the end wall extensions to clamp the parts in operative position, and a central core within the mold.

2. A trough mold including a bottom, end walls hinged thereto, inward extensions carried by the opposite ends of the end walls, bodily removable sides for the mold, each side having an angular extension projecting in the same direction, the inner faces of the side walls converging downwardly, the outer faces of the extensions adapted to lie juxtaposed to the inner faces of the end wall extensions, straps adapted to clamp the parts in operative position, and a central core within the mold.

3. A trough mold comprising a bottom, end walls hinged thereto, inward extensions carried by the end walls and positioned laterally of the sides of the bottom, side members having angular extensions positioned on the mold bottom with the outer sides of the extensions engaging the end wall extensions in a manner to present rectangular pockets at opposite ends of the mold, and a V-shaped central core removably positioned therein.

4. A mold comprising a bottom, end walls hinged thereto and side walls operatively associated with the end walls and bodily removable from the mold, the end walls being wider than the distance between the side walls and spaced therefrom, means extending between the side and end walls, and means for securing the side walls in engagement with the last named means.

5. A mold including a bottom, end walls and side walls, one set of walls being hinged to the bottom and the outer set of walls being loosely supported thereon and bodily

removable therefrom, the end walls being wider than the distance between the side walls and spaced there from, means extending between the side and end walls, means for clamping the parts together, and one set of walls adapted to be moved relative to the bottom to permit movement of the other set of walls when the plastic material is set in the mold.

In testimony whereof I affix my signature.

JOHN ^{his}
_{mark} KRONSER.

In presence of—

ELIZABETH ARLITT,
HOMER H. BENTON.
